US0D1094015S

(12) **United States Design Patent** (10) **Patent No.:** **US D1,094,015 S**
(45) **Date of Patent:** **** Sep. 23, 2025**

(54) **BLENDER JAR**

(71) Applicant: **Hamilton Beach Brands, Inc.**, Glen Allen, VA (US)

(72) Inventors: **Drew Carlson**, Glen Allen, VA (US); **Joseph Elliott**, Glen Allen, VA (US); **Kevin Leppert**, Glen Allen, VA (US)

(73) Assignee: **Hamilton Beach Brands, Inc.**, Glen Allen, VA (US)

(**) Term: **15 Years**

(21) Appl. No.: **29/886,045**

(22) Filed: **Mar. 3, 2023**

(51) LOC (15) Cl. **07-04**

(52) U.S. Cl. **D7/413**

CLAIM

The ornamental design for a blender jar as shown and described.

DESCRIPTION

FIG. 1 is a front perspective view of a first embodiment of a blender jar showing our design;

FIG. 2 is a front view thereof;

FIG. 3 is a rear view thereof;

FIG. 4 is a side view thereof;

FIG. 5 is an opposing side view thereof;

FIG. 6 is a top view thereof;

FIG. 7 is a bottom view thereof;

FIG. 8 is a cutaway view thereof;

FIG. 9 is a front perspective view of a second embodiment of a blender jar showing our design;

FIG. 10 is a front view thereof;

FIG. 11 is a rear view thereof;

FIG. 12 is a side view thereof;

FIG. 13 is an opposing side view thereof;

FIG. 14 is a top view thereof;

FIG. 15 is a bottom view thereof; and,

FIG. 16 is a cutaway view thereof.

The broken lines shown herein are for illustrative purposes only and form no part of the claimed design.

1 Claim, 16 Drawing Sheets
